UNITED STATES PATENT OFFICE

159,602

CONTAINER FOR COSMETICS OR THE LIKE

Helen A. Cornelius, New York, N. Y.

Application February 9, 1950, Serial No. 7,843

Term of patent 7 years

(Cl. D87—3)

To all whom it may concern:

Be it known that I, Helen A. Cornelius, a citizen of the United States, residing in New York, county of New York, and State of New York, have invented a new, original, and ornamental Design for a Container for Cosmetics or the like, of which the following is a specification, reference being had to the accompanying drawings, forming part thereof, in which:

Fig. 1 is a perspective view of a container for cosmetics or the like embodying my new design, illustrating the cover and bottom in separated position.

Fig. 2 is a perspective view of the container in a closed position.

I claim:

The ornamental design for a container for cosmetics or the like, as shown.

HELEN A. CORNELIUS.
